UNITED STATES PATENT OFFICE.

EDWARD F. McCOOL, OF VICTOR, COLORADO.

CLASSIFIER.

1,310,917.

Specification of Letters Patent.

Patented July 22, 1919.

Application filed October 9, 1917. Serial No. 195,512.

To all whom it may concern:

Be it known that I, EDWARD F. McCool, a citizen of the United States, residing at Victor, county of Teller, and State of Colorado, have invented certain new and useful Improvements in Classifiers; and I do declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to improvements in classifying means, my object being to provide a device of this character which shall prevent any pulverulent material beyond a predetermined size, from passing from the pulverizer through a conduit in which the classifier is interposed.

While the invention is capable of employment in many different relations, the contemplated use and that illustrated in the drawing, is in connection with means for pulverizing coal and passing the same from the pulverizer through a conduit to the furnace or furnaces or fire boxes in which fuel is to be consumed.

In constructions of this kind the pulverulent coal is delivered to the fire box through the medium of air pressure preferably by the use of a blower surrounding grinding disks through the instrumentality of which the coal is pulverized, the blower consisting of fan blades located in a chamber surrounding the pulverizing chamber or that where the grinding disks are located.

My improved classifier consists of a casing arranged in suitable proximity to the blower of the pulverizer and in such relation thereto that the chamber of the casing is inclined to such a degree that the coarser particles which are rejected by the classifier, may return by gravity and by way of a separate by-pass, to the pulverizer for re-treatment. In the chamber of the classifier casing and directly in front of the discharge nozzle leading from the blower is an adjustable baffle plate, while above this baffle plate and out of alinement with the blower nozzle, is a compartment through which the finely pulverized material may escape after entering the chamber of the casing, providing it is sufficiently fine to rise into the path

of the upper compartment, in which event the air current produced by the blower will carry this finely pulverized material through the conduit into the furnace or fire box where it is to be used. The baffle within the classifying chamber may be located more or less in the rear of the inlet extremity of the upper compartment through which the finely pulverized comminuted material must pass. The finer the material must be before it passes to the furnace, the greater will be the distance between the baffle plate and the inlet extremity of the pulverulent fuel compartment of the classifier, since the farther the baffle plate is located forward of the inlet extremity of the pulverulent compartment of the classifier, the more difficult will it be for the pulverized material to escape from the chamber of the classifier, since, after this material is discharged upon the baffle plate, there is a rebound or recoil action, and only the very fine material or that in the form of dust will rise and get into alinement with the upper compartment of the classifying chamber; while the coarser particles will fall to the bottom of the inclined chamber and slide downwardly into and through a special conduit or by-pass and return to the pulverizer, as heretofore stated.

Having briefly outlined the invention, I will proceed to describe the same in detail, reference being made to the accompanying drawing, in which is illustrated an embodiment thereof. In this drawing,—

Figure 1 is an elevation of my improved classifier shown in connection with a conduit partially in section, through which the pulverulent material may pass from the pulverizer which is shown in end elevation, to the fire box of a furnace whose front wall is shown in vertical section.

Fig. 2 is a sectional view of the classifier, shown in detail and on a somewhat larger scale.

Fig. 3 is a top plan view illustrating my improvement in duplex form, two pulverizers being shown, the conduit being bifurcated at both extremities, the two members at the discharge end communicating with a corresponding number of doors of a single fire box or of two fire boxes as may be desired.

Fig. 4 is a section taken on the line 4—4, Fig. 5.

Fig. 5 is a section taken through one of the feed openings of the fire box, the same being taken on the line 5—5, Fig. 4.

The same reference characters indicate 5 the same parts in all the views.

Let the numeral 5 designate a pulverizer equipped at one extremity with a blower 6, the pulverizer having an inlet conduit 7 for the material to be pulverized and an out-

10 let conduit or discharge nozzle 8 for the pulverized material. This discharge nozzle projects into the chamber 9 of a casing 10 which is inclined from its outer extremity downwardly, its lower extremity having an

15 exit port 12 for particles of solid material, the said port registering with a return conduit 13 which communicates with the feed conduit 7, whereby the solid or too coarsely pulverized particles are returned to the 20 grinder for retreatment. The casing 10 inclosing the chamber 9 is virtually divided into two compartments 14 and 15, the compartment 14 being provided with an adjustable baffle plate 16 which is equipped

25 with a stem 17 protruding exteriorly from the chamber and adjustable to regulate the space between the discharge extremity of the nozzle 8 and the baffle plate. The compartment 15 within the chamber 9 consists of an

30 open-ended tubular member 18 whose outer extremity telescopes in the adjacent extremity of a conduit member 19 which projects into the chamber 9 a short distance and also extends beyond the same. The inner 35 extremity of the tubular member 18 is equipped with a yoke 20 with which is connected as shown at 21 a rod or stem 22 which is slidable freely in a perforation 23 formed in the adjacent extremity of the casing 10.

40 This tubular member 18 forming the compartment 15 is readily adjustable within the casing 10, whereby its inlet extremity 24 may be spaced a greater or less distance from the baffle plate 16.

45 The conduit member 19, is preferably equipped with a damper 25 controlled by an exposed handle 2.

It will be noted that two pulverizing members 5 are shown and a corresponding 50 number of classifiers each composed of a casing 10, an adjustable baffle 16 and an adjustable open-ended tubular member 18, as heretofore explained. The two conduit members 19 are connected with a crotch-shaped conduit member 26 which is connected at its forward extremity with a central single conduit member 27, the forward extremity of the latter communicating with a second crotch-shaped member 28, the forward 55 extremities of the latter communicating respectively with two conduit members 29 which are in communication with feed openings 30 of a fire box 31 by means of discharge nozzles 32. The inlet openings 30 60 are each equipped with a thimble 33 con-

taining pins or projections 34 adapted to break up and distribute the pulverulent material as it enters the fire box of the furnace which may be designated in its entirety by the numeral 35. Each of the parts of the 70 crotch-shaped conduit member 28 is preferably equipped with a damper 36 of substantially the same construction as the dampers 25 of the conduit members 19.

From the foregoing description the use 75 and operation of my improved classifier will be readily understood. The material to be fed to the furnace is pulverized in one or more pulverizers 5 and discharged through the medium of a blower 6 and a discharge 80 nozzle 8 into the chamber 9 of the casing 10, in which chamber it first strikes the baffle plate 16. The very finely comminuted material, being reduced to a fine or dust-like form or an impalpable powder, will rise 85 after striking the baffle plate and enter the inner open end 24 of the tubular member 5 of the classifier and pass thence under the influence of the air current from the blower, through the conduit structure into the 90 furnace or fire box; while the coarser material or that which is not pulverized to the necessary degree of fineness for the purpose, will drop to the lowest part of the chamber 9 and slide down through the port 12 and 95 conduit 13 and return thence to the pulverizer for retreatment. It will be noted by referring to Figs. 1 and 2 of the drawing that the discharge nozzle 8 protrudes a considerable distance into the chamber 9 and 100 forwardly or inwardly beyond the escape port 12 for the solid particles of matter. In this way the said solid particles are allowed to settle beyond the path of the draft from the blower, and return to the pulverizer through the route heretofore explained. 105

Having thus described my invention, what I claim is,—

1. A classifier comprising an impervious casing having an inlet opening at one end and a discharge opening at the opposite end, the two openings being wholly out of alignment, a baffle arranged in the casing forward of and spaced from the inlet opening, and an open-ended conduit member mounted 110 in the casing in the rear of and in communication with the discharge opening, the rear end of the said conduit member being in communication with the chamber of the casing, the said baffle being adjustable flatwise toward and away from said inlet opening. 115

2. A classifier comprising an impervious casing having an inlet opening at one end and a discharge opening at the opposite end, the two openings being wholly out of alignment, a baffle arranged in the casing forward of and spaced from the inlet opening, and an open-ended conduit member mounted in the casing in the rear of and in communication with the discharge opening, the rear 120 130 135

end of the said conduit member being in communication with the chamber of the casing, the said conduit member being adjustably mounted in the casing, and said baffle 5 being adjustable flatwise toward and away from said inlet opening.

3. A classifier comprising an impervious casing occupying a position downwardly inclined from its forward extremity, said casing having outlet and inlet openings respectively formed in its front and rear walls, said openings being arranged wholly out of alinement with each other, a baffle plate arranged in front of but at some distance from 10 the inlet opening, a conduit member passing through the inlet opening and projecting some distance into the chamber of the casing, the latter having a relatively small outlet opening formed in its rear wall for the 15 escape of the relatively coarse particles of the material under treatment.

4. A classifier comprising an impervious casing having a downwardly inclined lower wall, an outlet opening arranged in its front 25 wall and an inlet opening in its rear wall, said openings being arranged wholly out of alinement with each other, a baffle plate arranged opposite said inlet opening and

parallel to said rear wall, a conduit extending into said casing from said outlet opening and having its mouth in the rear of said baffle plate, and an opening in the lower part of said casing for escape of large particles. 30

5. A classifier comprising an impervious 35 casing having a downwardly inclined lower wall, an outlet opening arranged in its front wall and an inlet opening in its rear wall, said openings being arranged wholly out of alinement with each other, a baffle plate arranged opposite said inlet opening and 40 parallel to said rear wall, a conduit extending into said casing from said inlet opening and directed toward said baffle plate, the baffle plate being adjustable flatwise toward 45 and from said conduit, a conduit extending into the casing from the outlet opening and being longitudinally adjustable to vary the distance of its mouth from the rear wall.

In testimony whereof I affix my signature, 50 in presence of two witnesses.
